ART OF CRACKING HYDROCARBON OILS.

Application filed June 11, 1927. Serial No. 198,253.

This invention relates to improvements in the cracking of heavier and higher boiling hydrocarbon oils, such as gas oil, to produce therefrom lighter and lower boiling hydrocarbon oils, such as gasoline and gasoline-containing pressure distillates. More particularly, the present invention relates to improvements in operations described in application Serial No. 704,926, filed April 8, 1924 10 which has matured into Patent 1,634,666.

According to the present invention, a charge of oil is circulated in a pressure still made up of a bulk supply drum, a battery of heating tubes and circulating connections 15 for circulating and recirculating oil from the bulk supply drum through the heating tubes and back to the bulk supply drum, and a body of finely divided absorbent or desulphurizing or filtering material is maintained 20 in the bulk supply drum above suitable supporting means extending entirely across the path of the circulating still charge, as described in the said prior application, and the body of finely divided material above the 25 supporting means in the bulk supply drum is agitated to promote intimate contact between the finely divided material and the circulating oil and to assist in maintaining free circulation of the still charge. This agitation of the body of finely divided absorbent 30 or desulphurizing or filtering material may be effected by mechanical means or by directed discharge of the oil entering the bulk supply drum from the heating tubes or by 35 introduction of a gaseous agitating medium into the body of oil in the bulk supply drum. The introduction of a gaseous agitating medium is a particularly advantageous method of operation, and it is particularly 40 advantageous to introduce such a gaseous agitating medium beneath the supporting means in the bulk supply drum. The introduction of a gaseous agitating medium also assists in promoting complete separation of light components 45 from the circulating still charge and in maintaining the still pressure.

The invention will be further described in connection with the accompanying drawings which illustrate, in a diagrammatic and conventional manner, in elevation and partly in

section and with parts broken away, an apparatus embodying the invention and adapted for carrying out the process of the invention; but it is intended and will be understood that this more detailed description and illustration are intended for the purpose of exemplification and that the invention is not limited thereto. 55

Referring to the drawings, the pressure still illustrated comprises a bulk supply drum 60 1, a battery of heating tubes 2 arranged in the heating flue of a furnace 3, and circulating connections 4, 5 and 6 including a circulating pump 7 for circulating oil from the bulk supply drum through the heating tubes 65 and back to the bulk supply drum. Suitable supporting means 8 adapted to retain the finely divided material used but to permit free passage of oil are arranged in the bulk supply drum below the normal liquid 70 level therein and extending entirely across the bulk supply drum between the circulating connections 4 to the heating tubes and the circulating connections 6 from the heating tubes. Vapors escape from the bulk supply drum 1 through the vapor line 9 to the lower end of the reflux tower 10 from the upper end of which vapors remaining uncondensed escape through vapor line 11 to the condenser 12 arranged to discharge into the 75 receiver 13. The distillate product is discharged from the receiver through connection 14 and uncondensed vapors and gases through connection 15. The pressure in the system may be maintained and regulated by means 80 of valve 16 or by suitable valves arranged beyond the condenser or receiver. Connection 17 is provided for introducing raw oil into the upper end of the reflux tower 10. Reflux condensate, and any admixed unvaporized raw oil, is returned to the pressure 85 still proper through return line 18. Connection 19 is provided for supplying cool oil to the bearings of the circulating pump 7. Raw oil in excess of that required to cool and lubricate the pump bearings may be forced into the circulating still charge through the pump 90 bearings by means of this connection. Connection 20 is provided for pumping out the still at the end of a run and for initially 95 100

charging the still at the beginning of a run. Connection 21 is provided for discharging pitch-laden oil or tar from the still during operation.

5 A perforated pipe 22 is arranged in the bulk supply drum beneath the supporting means 8. The perforations may be arranged in rows on opposite sides toward the lower side of this pipe, as illustrated, or they may 10 be arranged in one or more rows on the upper side of this pipe. Connection 23 communicates with this perforated pipe 22. In one advantageous construction, the circulating connections 6 are two in number and are arranged 15 adjacent opposite sides of the bulk supply drum, as illustrated, and a single perforated pipe 22 is arranged centrally beneath the supporting means 8. In place of a single perforated pipe, such as that illustrated, several such perforated pipes may be used and they may be arranged transversely or longitudinally of the bulk supply drum. A compressor or other suitable forcing means (not shown in the drawings) for the introduction 20 of a gaseous agitating medium is connected to connection 23.

The supporting means 8 may comprise one or more screens of suitable mesh arranged between perforated plates, as described in the 30 said prior application, or more advantageously these supporting means may comprise one or more screens of suitable mesh arranged between gratings as described in application Serial No. 184,296, filed April 16, 1927.

35 In operation, a body of finely divided absorbent or desulphurizing or filtering material is maintained in the bulk supply drum 1 above the supporting means 8. This body of finely divided material may be, for example, finely divided fuller's earth, pulverized coke or calcined bauxite. Fuller's earth is a particularly advantageous material as it seems to combine in itself valuable absorbent, desulphurizing and filtering properties. In 40 the accompanying drawings, this body of finely divided material is shown at rest; in operation this body of finely divided material is agitated by the introduction of a gaseous medium through the perforated pipe 45 22 and is maintained in suspension or partly in suspension in the body of oil in the bulk supply drum above the supporting means 8. Suspended absorbent or desulphurizing or filtering material may be discharged during 50 the operation in the pitch-laden oil or tar discharged through connection 21, and to make up for this discharge of the finely divided material, additional finely divided material may be supplied in suspension in raw 55 oil supplied to the operation.

The following example will further illustrate the invention: In a still of the type illustrated, in which the bulk supply drum is about 9 feet in diameter and 40 feet long, 60 the initial charge of finely divided material

may consist of from 3½ to 5 tons of 40-60 mesh fuller's earth. The still is initially charged with about 8,000 gallons of gas oil and the still charge brought to cracking conditions of temperature and pressure in the usual way. For the production of gasoline from a gas oil character stock, the still may be operated under a pressure in the neighborhood of 125 pounds per square inch and the still charge maintained at an approximately 70 corresponding temperature. It will be understood, however, that higher or lower pressures may be used; for example, pressures as high as 300 pounds per square inch or higher may be used, particularly with stocks containing substantial proportions of kerosene character components. After the still is brought to operating conditions, the introduction of raw oil is begun. The introduction of raw oil through the reflux tower is 80 regulated to condense and reflux those components of the vapors heavier than desired as components of the distillate product. Before the concentration of pitch-like constituents in the circulating still charge reaches an objectionable value, the discharge of pitch-laden oil or tar is started. At this point in the operation, the distillate product taken off may amount to about 1,000 gallons per hour, the discharged pitch-laden oil or tar to 90 about 1,500 gallons per hour and the raw oil supplied to about 2,500 gallons per hour. Raw oil in excess of that introduced into the reflux tower is supplied directly to the circulating still charge. Before the body of 100 fuller's earth maintained in the bulk supply drum above the supporting means is seriously depleted, the introduction of fine fuller's earth in suspension in raw oil supplied to the operation is begun. From $\frac{1}{4}$ to $\frac{3}{4}$ pound per barrel of oil, for example, may be supplied in suspension in the raw oil introduced into the reflux tower. This fuller's earth introduced in suspension in the raw oil may be of the same mesh as that of the initial body, or it may be finer, for example of 60-100 mesh. Likewise, during operation, gas is introduced beneath the supporting means in the bulk supply drum at a rate approximating 110 150-250 cubic feet per minute. 115

Although other gases or gas mixtures are useful in carrying out the invention, particularly other hydrocarbon gas mixtures, it is advantageous to employ for the gaseous agitating medium a hydrocarbon gas mixture 120 such as that remaining uncondensed after condensation of the distillate product from the pressure still. The gas mixture discharged through connection 15 in the apparatus illustrated, for example, may be reintroduced through connection 23. This gas mixture may be reinforced by hydrocarbon gases from other sources, such as other pressure stills, as required, or part of the gas mixture may be discharged from the system as 125 130

may be necessary in regulation of the pressure. In one advantageous method of operation, in order to economize with respect to power required in introducing the gaseous 5 agitating medium, the still pressure may be maintained through the condenser and receiver and the agitating gaseous medium maintained in circulation in a closed cycle under pressure throughout the cycle.

10 The present invention may be employed throughout the operation of the pressure cracking still, that is the introduction of the gaseous agitating medium may be begun as soon as the still is brought to operating conditions 15 of temperature and pressure and continued throughout the remainder of the run; or the invention may be used only during the latter part of a run, that is the introduction of the gaseous agitating medium may be 20 started only after the pressure cracking still has been in operation for some time or toward the end of a run.

We claim:

1. An improved method of cracking hydrocarbon oils, which comprises circulating a charge of oil in a pressure still from a bulk supply drum through heating tubes back to the bulk supply drum and maintaining a body of finely divided absorbent material 30 in the bulk supply drum above supporting means adapted to retain the finely divided absorbent material but to permit free passage of oil and extending entirely across the path of the circulating still charge, heating the oil to a cracking temperature in the heating tubes, taking off vapors including 35 vapors of the desired product under pressure, and agitating the body of finely divided absorbent material in the bulk supply drum.

2. An improved method of cracking hydrocarbon oils, which comprises circulating a charge of oil in a pressure still from a bulk supply drum through heating tubes back to the bulk supply drum and maintaining a body of finely divided absorbent material in the bulk supply drum above supporting means adapted to retain the finely divided absorbent material but to permit free passage of oil and extending entirely across the path of the circulating still charge, heating the oil to a cracking temperature in the heating tubes, taking off vapors including 50 vapors of the desired product under pressure, and agitating the body of absorbent material in the bulk supply drum by the introduction of a gaseous agitating medium.

3. An improved method of cracking hydrocarbon oils, which comprises circulating a charge of oil in a pressure still from a bulk supply drum through heating tubes back to the bulk supply drum and maintaining a body of finely divided filtering material in the bulk supply drum above supporting means adapted to retain the finely divided

filtering material but to permit free passage of oil and extending entirely across the path of the circulating still charge, heating the oil to a cracking temperature in the heating tubes, taking off vapors including vapors of the desired product under pressure, and introducing a gaseous agitating medium beneath the supporting means in the bulk supply drum.

4. An improved method of cracking hydrocarbon oils, which comprises circulating a charge of oil in a pressure still from a bulk supply drum through heating tubes back to the bulk supply drum and maintaining a body of fuller's earth in the bulk supply 75 drum above supporting means adapted to retain the fuller's earth but to permit free passage of oil and extending entirely across the path of the circulating still charge, heating the oil to a cracking temperature in the heating tubes, taking off vapors including 80 vapors of the desired product under pressure, and agitating the body of fuller's earth in the bulk supply drum.

5. An improved pressure still for cracking hydrocarbon oils, comprising a bulk supply drum and a battery of heating tubes and circulating connections for circulating oil from the bulk supply drum through the heating tubes back to the bulk supply drum, a vapor 90 outlet from the bulk supply drum, supporting means adapted to retain finely divided solid material but to permit free passage of oil arranged in the bulk supply drum below the normal liquid level therein and extending 95 entirely across the bulk supply drum between the circulating connections to the heating tubes and the circulating connections from the heating tubes, and means for agitating finely divided solid material in the bulk supply drum above the supporting 100 means.

6. An improved pressure still for cracking hydrocarbon oils, comprising a bulk supply drum and a battery of heating tubes and 110 circulating connections for circulating oil from the bulk supply drum through the heating tubes back to the bulk supply drum, a vapor outlet from the bulk supply drum, supporting means adapted to retain finely divided solid material but to permit free passage of oil arranged in the bulk supply drum below the normal liquid level therein and extending 115 entirely across the bulk supply drum between the circulating connections to the heating tubes and the circulating connections from the heating tubes, and means for agitating finely divided solid material in the bulk supply drum above the supporting 120 means.

7. An improved method of cracking hydrocarbon oils, which comprises circulating a charge of oil in a pressure still from a bulk supply drum through heating tubes back to the bulk supply drum and maintaining a 130

body of desulphurizing material in the bulk supply drum above supporting means adapted to retain the desulphurizing material but to permit free passage of oil and extending 5 entirely across the path of the circulating still charge, heating the oil to a cracking temperature in the heating tubes, taking off

vapors including vapors of the desired product under pressure, and agitating the body of desulphurizing material in the bulk supply drum. 10
